(57) **CLAIM**

The ornamental design for a clamp with indicator, as shown and described.

DESCRIPTION

FIG. 1 is a perspective view of a clamp with indicator, wherein a slide is shown in a first position;

FIG. 2 is a front view thereof;

FIG. 3 is a rear view thereof;

FIG. 4 is a right-hand side view thereof;

FIG. 5 is a left-hand side view thereof;

FIG. 6 is a top view thereof;

FIG. 7 is a bottom view thereof;

FIG. 8 is an alternative perspective view of the clamp with indicator; and,

FIG. 9 is a perspective view of the clamp with indicator as shown in FIG. 1, wherein the slide is shown in an alternative position.

The broken lines of all the Figures shown do not form part of the claimed design.
